BUDGET BANK

Earnest F. Wilkinson, Aurora, Ill.

Application March 26, 1941, Serial No. 385,367

1 Claim. (Cl. 232—4)

This invention relates to new and useful improvements in deposit receptacles and more particularly to a budget device in the form of a bank, the principal object of the invention being to provide a bank of this character in which funds can be deposited for various future obligations.

Another object of the invention is to provide a budget bank having a plurality of depositories for money and complementary indicating and direction means, explaining various indebtedness and directions for distributing and paying the same.

Another important object of the invention is to provide a deposit receptacle of the character stated in which funds can be distributed on pay-day to cover future obligations and in which are located readily accessible containers or drawers for bills and receipts.

Other objects and advantages of the invention will become apparent to the reader of the following specification.

In the drawings:

Figure 1 is a fragmentary top plan view of the bank with the lid in open position.

Figure 2 is a transverse sectional view taken substantially on the line 2—2 of Figure 1 with the drawer and lid in closed position.

Figure 3 is a fragmentary enlarged plan view of the bank with the lid removed.

Figure 4 is a fragmentary perspective view of the till.

Figure 5 is a perspective view of one of the slides.

Figure 6 is a fragmentary detailed sectional view taken substantially on the line 6—6 of Figure 2.

Referring to the drawings wherein like numerals designate like parts, it can be seen in Figure 2 that numeral 5 denotes a drawer bottom, shelf or other supporting structure upon which the bank generally referred to by numeral 6 can be secured. This support 5 is formed to receive a plug 7 which has a head 8 abutting the bottom side of the support 5. The plug 7 extends upwardly, terminating above the top of the support 5 and this portion of the plug is threaded to accommodate nuts 9 and 10. This end portion of the plug 7 is internally threaded to receive the lower threaded end portion 11 of a retaining rod 12.

The bank consists of a metal box 13, open at its top. To the top edge of the box 13 is hinged secured as at 14, a lid 15 which can be secured to the box by a key lock 16.

As shown in Figure 2, numeral 17 generally

refers to a till which in construction consists of a bottom 18, side walls as at 19 and end walls 20. Partitions 21 and 22 extend longitudinally and transversely in the till to divide the till into a plurality of money receptors. Cleats as at 23 extend along the inner surfaces of the side walls of the box 13 to support the till 17 in the manner substantially shown in Figure 2 with its upper edge terminating immediately below the upper edge of the box 13.

A cover plate 24 is provided for the till and this cover plate has longitudinal parallel rows of slots 24a through which money can be dropped into corresponding compartments of the till 17. Adjacent each slot 24a is a card suitably held in place, this card being denoted by numeral 25. Each card 25 contains suitable information as to what deposits through corresponding slot 24a are for and in what amounts they should be deposited.

Guide means 26 are provided under the cover plate 24, these guide means being in the form of guide lugs struck from the cover plate 24 in forming the slot 24a. In these guides are slidable slides 27, each of these slides having a knob 28 connected by a neck portion 29 to the plate 27 and this neck portion rides in a guide slot 30 in the cover plate 24. Each of the slides 27 is formed with a slot 31 registrable with the corresponding slot 24a by sliding the slide 27. On one side of the slide 27 may be the letters O. K. which may be made visible through the corresponding slot 24a by shifting the slide 27, as when sufficient money has been deposited in the underlying money receiving compartment, or when further funds are to be added to the collection, the slide may be moved in the opposite direction. The word "Attention" at the opposite side of the slot 31 may be made visible through the corresponding slot 24a by shifting the slide 27.

The retaining rod 8 extends upwardly through the till 17 and through an opening in the cover plate 24 and the upper end of this rod has a knurled removable knob or nut 33. Obviously by removing this knob 33, the cover plate 24 can be lifted to permit access to the contents of the various money compartments in the till 17.

The lower portion of the box 13 has a pair of drawers one of which is shown at 34, slidable through openings in the front wall of the box 13 and which are useful for holding bills and receipts. Guides as at 36 are provided, one for each of the drawers. Suitable handles 38 are provided at the ends of the box 13 whereby the box can be conveniently carried after it has been detached from a supporting structure 5.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A budget bank comprising a till having compartments therein for coins, a cover plate for the 10 till having slots therein for the deposit of coins

therethrough into said compartments, and slides for closing and opening said slots adjustable on said plate into different positions and having slots therein for registration with the slots in the cover plate in one position of said slides and provided with different data thereon upon opposite sides of the slots therein for display through the slots in said plate in other positions of said slides in which the slots in said slides are out of registration with the slots in said cover plate.

EARNEST F. WILKINSON.
